US0D1075754S

(12) **United States Design Patent** (10) **Patent No.:** **US D1,075,754 S**
(45) **Date of Patent:** **** May 20, 2025**

(54) **SMART WATCH**

(71) Applicant: **Creek Wearable Technology Co., Ltd.**,
Shenzhen (CN)

(72) Inventors: **An He**, Shenzhen (CN); **Kexin Tong**,
Shenzhen (CN)

(73) Assignee: **Creek Wearable Technology Co., Ltd.**,
Shenzhen (CN)

(**) Term: **15 Years**

(21) Appl. No.: **35/521,007**

(22) Filed: **Apr. 16, 2024**

(80) **Hague Agreement Data**

Int. Filing Date: **Apr. 16, 2024**

Int. Reg. No.: **DM/237083**

Int. Reg. Date: **Apr. 16, 2024**

Int. Reg. Pub. Date: **May 24, 2024**

(30) **Foreign Application Priority Data**

Jan. 26, 2024 (CN) 202430053898.3

(51) **LOC (15) Cl.** **14-02**
